UNITED STATES PATENT OFFICE.

GEORGE W. BUSKIRK, OF NEW YORK, N. Y.

DESIGN FOR PAPER.

SPECIFICATION forming part of Design No. 35,928, dated June 3, 1902.

Application filed August 8, 1901. Serial No. 71,415. Term of patent 7 years.

To all whom it may concern:

Be it known that I, GEORGE W. BUSKIRK, a citizen of the United States, residing in the borough of Manhattan, in the county of New York and State of New York, have invented a certain new and useful Design for Paper, of which the following is a specification.

This invention relates to a design for paper, as will hereinafter more fully appear, reference being had to the accompanying drawing, wherein is represented a view of a sheet of paper having the surface thereof ornamented with my new design.

As shown in the drawings, the leading or material feature of my design consists of a series of pairs of comparatively heavy parallel lines *a*, extending diagonally across the surface of the paper sheet from the upper to the lower edge thereof, said diagonal lines being intersected and crossed substantially at right angles by a number or plurality of series of very short lines *b*, as shown. The spaces between the pairs of lines *a* are some-

what wider than the spaces between the lines of each pair thereof, and intermediate the said lines and parallel therewith are relatively fine lines *c*, which cross the shorter lines *b* also substantially at right angles. The said shorter lines *b* of each series thereof are in parallelism, and they are disposed or organized in sinuous curves or directions across the surface of the paper sheet, forming waves extending from one vertical edge of the sheet to the other. The crest portions, sides, and troughs of the waves thus produced by the plurality of series of said short lines *b* are also in parallelism, as shown.

Having described my invention, what I claim as new, and desire to secure by Letters Patent, is—

The design for paper as herein shown and described.

GEORGE W. BUSKIRK.
